United States Patent Office

Des. 210,275
Patented Feb. 27, 1968

210,275

ELEVATED BUILDING

Shelby Johnson and Ernest S. Johnson, both of 660 62nd St., San Diego, Calif. 92114

Filed June 30, 1967, Ser. No. 7,657

Term of patent 14 years

(Cl. D13—1)

I claim:

The ornamental design for an elevated building, as shown and described.
